UNITED STATES PATENT OFFICE.

FRANK H. FULLER, OF KITTERY POINT, MAINE.

AIR MOISTENER.

Application filed November 11, 1924. Serial No. 749,146.

To all whom it may concern:

Be it known that I, FRANK H. FULLER, a citizen of the United States, residing at Kittery Point, in the county of York and 5 State of Maine, have invented certain new and useful Improvements in Air Moisteners, of which the following is a specification.

This invention relates to air moisteners for hot air furnaces and it has for its object 10 to provide an improved device for supplying water vapor to the hot air generated by the furnace, the improvement being of such nature that it may readily be applied to existing furnaces, and the device including 15 means for maintaining a continuous supply of water to the vaporizer tank so as to keep it at a certain level.

Various improvements in the apparatus will be apparent from the following description and the accompanying drawings, in which Fig. 1 is a side elevation of the furnace showing the vaporizer applied thereto. Fig. 2 is a section on the line 2—2 of Fig. 1. Fig. 3 is a detail in section of the 25 water tank and connections.

Referring specifically to the drawings, 6 indicates the fire pot of an ordinary hot air furnace, and the vaporizer is disposed in the air space between the fire pot and the ordinary outer shell 7 of the furnace.

The vaporizer comprises a water tank 8 with a float valve 9 controlling the inlet through the supply pipe 10, whereby the water is maintained at a desired level. 11 35 is an overflow pipe. This tank is closed at the top, but the top or cover has a series of openings 12 through which vapor may escape. A ring pipe 13 is connected at its ends to the upper part of the tank, above 40 the water level, and this pipe has a plurality of jet holes 14.

From a point opposite the tank the pipe 13 inclines downwardly at both sides to the tank, the purpose of this being to return water of condensation to the tank. 45

It is obvious that the tank and pipe connections can be readily set up between the fire pot and the shell of the furnace.

In operation, water is vaporized in the tank by the heat of the furnace and the vapor escapes through the openings 12 and 14 and moistens the air delivered by the furnace, thereby accomplishing the result of the apparatus. It is to be noted that the tank, being closed except for the small perforations 12, will not collect dust and dirt from ashes and the like, and the pipe 13 extends all the way around the fire pot so that all parts of the air are moistened. Nothing but vapor escapes through the openings 12 and 14 and any condensation will by the inclination of the pipe be returned to the tank, so that the fire pot and ashpit will not become rusty. The supply is automatic, the water being renewed to a constant level as 65 it evaporates, so that the amount of vapor supplied depends on the state of the fire. 60

I claim:

An air moistener for hot air furnaces comprising a water tank having a perforated 70 top, and a pipe connected at both ends to the tank above the water level therein and provided with holes for the outlet of vapor, said pipe extending around the fire pot, and both sides of the pipe being inclined downwardly toward the tank, whereby condensation is returned to the tank. 75

In testimony whereof, I affix my signature.

FRANK H. FULLER.
